RETRACTABLE CLOTHESLINE HANGER

Guy B. Carroll, Minneapolis, Minn.

Application December 10, 1945, Serial No. 633,907

12 Claims. (Cl. 211—119.16)

1

My present invention relates to improvements in clothesline hangers and, more particularly, to such a hanger that is retractable.

The principal object of this invention is to provide a retractable hanger, usable in pairs to hold a clothesline threaded back and forth therebetween and when retracted, carries the clothesline laterally therewith without changing its attachment or relation thereto.

A further object of this invention is to provide a retractable clothesline hanger having a novel latch for holding the same retracted.

Other objects of the invention will be apparent from the following description, reference being had to the drawings.

To the above end, generally stated, the invention consists of the novel construction and arrangement hereinafter described and defined in the claims.

In the accompanying drawings, which illustrate the invention, like characters indicate like parts throughout the several views.

Referring to the drawings:

Fig. 1 is a top view of two of the retractable hangers attached to overhead joist, and having a clothesline threaded back and forth therebetween;

Fig. 2 is a side elevation of the parts shown in Fig. 1, and further showing intermediate joist;

Fig. 3 is a front elevation of one of the hangers shown in Fig. 2 with the clothesline sectioned on the line 3—3 of Fig. 1, said view also showing the hanger in a retracted position by means of broken lines;

Fig. 4 is a fragmentary detail view with some parts sectioned on line 4—4 of Fig. 3, on an enlarged scale;

Fig. 5 is a detail view partly in elevation and partly in section taken on the line 5—5 of Fig. 3, and on the same scale as Fig. 4;

Fig. 6 is a fragmentary detail view partly in elevation and partly in section taken on the line 6—6 of Fig. 3, on the same scale as Fig. 4;

Fig. 7 is a rear elevational view of the parts shown in Fig. 6 removed from the joist; and

Fig. 8 is a fragmentary detail view showing the latch in section taken on the line 8—8 of Fig. 7, and also showing one of the links in contact with the cam plate.

The numeral 8 indicates two outer joist and the numeral 9 indicates two inner joist that afford support for the clothesline hangers.

Two of the retractable hangers A and B are employed to hold a clothesline 10 threaded back and forth therebetween. These two holders A

2

and B are turned toward each other and each thereof includes a horizontal rectangular frame 11 comprising a pair of end bars 12, front and rear crossbars 13 and 14, respectively, and an oblique crossbar 15. These bars 12, 13, 14 and 15 are all rigidly connected. The end portions of the end bars 12 are turned downwardly to afford hinge lugs 16.

Upstanding ears 17 overlap the rear pair of hinge lugs 16, outwardly thereof and are secured thereto by headed rivets 18. The frames 11 extend transversely under the joist 8 and 9 with the ears 17 overlapping the joist 8, at their outer faces and are secured thereto by lag-screws 19. Said frames 11 are secured to the joist by screws 19'.

Horizontal angle bars 20 and 20' are held suspended from the frames 11 of the hangers A and B, respectively, by pairs of upright links 21 for endwise and upwardly swinging movement in vertical planes. These links 21, at their upper end portions, are pivoted on the rivets 18 and their lower end portions overlap the inner faces of the upturned flanges of the angle bars 20 and 20' and are pivoted thereto by headed rivets 22. The horizontal flanges of the angle bars 20 and 20' are turned toward each other.

Upwardly and outwardly inclined brace bars 23 extend from the angle bars 20 and 20' to the outer corners of the frames 11. The upper end portions of the brace bars 23 are bent into the form of right angles 24, the outer members thereof overlapping the inner faces of the outer hinge lugs 16 and are pivoted thereto by rivets 25. These braces 23, at their lower end portions, are bent downwardly parallel to the links 21, as indicated at 26 and pivoted on the rivets 22.

Secondary brace bars 27 connect the brace bars 23, at medial points, to the links 21, at their upper end portions. Obviously, the links 21, brace bars 23 and 27 afford end brackets 28. The angle bars 20 and 20' connect the end brackets 28 in pairs with freedom to swing laterally on the rivets 18 and 25 in vertical planes, transversely of the hangers A and B. Lateral swinging movement of the end brackets 28 will carry the angle bars 20 and 20' endwise and upwardly and position said brackets and angle bars, substantially in the same horizontal plane close to the under sides of the frames 11.

The clothesline 10 is attached to the angle bars 20 and 20' by upstanding headed studs rigidly secured to the horizontal flanges of said angle bars. These studs are spaced equidistantly apart longitudinally of the angle bars 20

and 20' and designated by the numeral 29, except for the end stud 30 on the angle bar 20 and the end stud 31. These studs 30 and 31 are on opposite ends of the angle bars 20 and 20'.

The clothesline 10 has in one of its end portions a loop 32 and in its other end portions a loop 32'. As shown, the loop 32 is placed over the stud 30, threaded back and forth between the angle bars 20 and 20' and passed around the studs 29. Primarily, the length of the clothesline 10 is such that when drawn taut, the loop 32' may be placed over the stud 31 to complete the attachment of the clothesline 10 to the hangers A and B. As stretch develops in the clothesline 10, the loop 32' may be removed from the stud 31 and the clothesline 10 placed around said stud and the loop 32' placed over one of two studs 33 on the angle bar 20 between the stud 31 and the adjacent stud 29, as shown. If further slack develops in the clothesline 10, the loop 32 may be removed from the stud 30, the clothesline 10 placed around said stud and the loop 32 placed over one of two studs 33' on the angle bar 20'.

To hold each hanger A and B retracted, to leave head room under said hangers and the clothesline 10, I provide a novel latch 34 therefor. As the two latches 34 are identical, the one with the other, the description of one will suffice for the other and hence the latch 34 for the hangers B will be described. This latch 34 is formed of a single round rod turnably mounted, near one of its end portions, in a bearing 35 on the under side of one of the end bars 12, close to the connected link 21. The bearing 35 holds the latch 34 for swinging movement transversely of the angle bar 20'. The short end of the rod is bent forwardly to afford a finger 36 that extends transversely under the crosstie bar 14, parallel thereto, and normally engages the same as a stop for the latch 34. The long end portion of the rod is bent, first rearwardly from the bearing 35, then downwardly, then forwardly to afford a supporting shoulder 37 on which the angle bar 20' rests when in a raised position, as shown by broken lines in Fig. 3 and full lines in Figs. 6 and 7. From the supporting shoulder 37, the rod is bent downwardly and rearwardly to afford an oblique cam member 38. Said rod, at the lower end of the cam member 38, is bent laterally parallel to the angle bar 20' to afford a fingerpiece 39.

The latch 34 is held in an operative position, with its stop finger 36 against the bar 14, by the force of gravity. Normally, the cam member 38 is in the path of movement of the angle bar 20' when being raised. A horizontal cam plate 40 extends transversely under the supporting shoulder 37 and is rigidly secured thereto at its longitudinal center. This plate 40 also curves upwardly on the cam member 38 on the outside thereof and reinforces said plate. The ends of the plate 40 converge from the curved portion of said plate to the outer end of the supporting shoulder 37 to afford cams 41.

Obviously, the hangers A and B may be raised or lowered without removing the clothesline 10 therefrom or changing its attachment thereto. Furthermore, there is no slack put in the clothesline 10 at any time, either during the raising or lowering of the hangers A and B or when the same are held retracted by the latches 34.

When raising the hangers A and B, the angle bars 20 and 20' engage the cam member 38 and thereby swing the latches 34 out of the paths of movement of said angle bars as shown by broken lines in Fig. 6. As the angle bars 20 and 20' pass

upwardly out of engagement with the cam members 38, the latches 34 are returned to operative positions by the force of gravity, and position the supporting shoulders 37 under the angle bars 20 and 20' and support the same when released, shown by full lines in Figs. 4 and 5.

To lower the hangers A and B, it is only necessary to take hold of the fingerpieces 39 and move the latches 34 into inoperative position, as one of which is shown by broken lines in Fig. 6.

During the return movement of the hangers A and B, the adjacent links 21 are in the paths of movement of the latches 34 and are moved out of said paths by the cams 41.

From what has been said, it will be understood that the retractable clothesline hanger described is capable of modification as to details of construction and arrangement within the scope of the invention disclosed and claimed.

What I claim is:

1. In a hanger of the class described, a horizontal frame having means for attaching the same to a support, said frame including end bars, the end portions of which are turned downwardly to afford front and rear pairs of hinge lugs, a bar having means for attaching a clothesline thereto, a pivoted pair of links suspending the bar from the rear pair of hinge lugs for endwise and upwardly swinging movement in a vertical plane, and pivoted braces extending from the lower end portions of the links to the front pair of hinge lugs.

2. In a hanger of the class described, a horizontal rectangular frame, a pair of end brackets pivoted to the frame for lateral upwardly swinging movement in a vertical plane below the frame, a bar pivoted to the brackets for endwise and upwardly swinging movement in said plane, said bar having means for attaching a clothesline thereto, said frame having upstanding ears for attaching the frame to an overhead support and holding the same in engagement with the support, the rear edge of the frame, the ears and the bar being substantially in the same vertical plane.

3. In a hanger of the class described, a horizontally disposed rectangular frame comprising a pair of end bars, front and rear crosstie bars and an oblique intermediate crosstie bar, the end portions of the end bars being turned downwardly to afford hinge lugs, depending end brackets pivoted to the hinge lugs for lateral upwardly swinging movement in a vertical plane, and a bar pivoted to the end brackets for endwise and upwardly swinging movement therewith in said plane, said bar having means for attaching a clothesline thereto, said frame having upstanding ears for attaching the same to a support, said crosstie bar, the last noted bar and the ears being in substantially the same vertical plane, said ears holding the frame in engagement with the support.

4. The structure defined in claim 3, further including a latch pivoted to the frame and having means for holding the end bracket and the bar retracted.

5. In a hanger of the class described, a frame having means for attaching the same to a support, a pair of end brackets pivoted to the frame and suspended therefrom for lateral upwardly swinging movement in a vertical plane, a bar pivoted to the end brackets for endwise and upwardly swinging movement therewith, said bar having means for attaching a clothesline thereto, and a latch on the hanger yieldingly held in an operative position for holding the end brackets and bar in their raised position, said latch being formed of

5

a single rod pivotally mounted near one of its end portions on the frame to turn about a horizontal axis, the short end portion of the rod being bent laterally to afford a finger that normally engages the frame as a stop and releasably holds the latch in an operative position, the long end portion of the rod at its bearing being bent first horizontally, then downwardly and again horizontally to afford a supporting shoulder that extends across the path of movement of the bar, said rod, at its supporting shoulder, being bent outwardly and downwardly to afford an oblique cam member that is engaged by the bar during its upwardly swinging movement and operates the latch to move its supporting shoulder out of said path of movement.

6. In a hanger of the class described, a frame having means for attaching the same to a support, a pair of end brackets pivoted to the frame and suspended therefrom for lateral swinging movement in a vertical plane, a bar pivoted to the end brackets for endwise and upwardly swinging movement therewith, said bar having means for attaching a clothesline thereto, and a latch having a supporting shoulder pivoted on the hanger, gravity held in an operative position and provided with a depending cam-acting member in the path of movement of one of the end brackets when the bar is swung upwardly, whereby the engagement of the end bracket with the cam-acting member will move the latch into an operative position and hold the same until the bar has passed the same and engaged the supporting shoulder.

7. In a hanger of the class described, a pair of parallel end bars having front and rear ends and applicable to an overhead support, a bar having means for attaching a clothesline thereto, a pivoted pair of links suspending the bar from the rear end of the end bars, and pivoted braces extending obliquely from the lower end portions of the links to the front end of the parallel end bars.

8. The structure defined in claim 7 in which all of the pivots of the links and the braces extend substantially parallel to the end bars.

9. The structure defined in claim 7, further including secondary braces attached to the upper end portions of the links and the intermediate portions of the first noted braces.

10. A self-contained hanger of the class described, comprising a horizontal rectangular frame having front and rear ends and applicable

to an overhead support, a bar having means for holding a clothesline, a pair of pivoted links holding the bar suspended from the rear end portion of the frame, and oblique pivoted braces connecting the bar to the front end portion of the frame.

11. In a hanger of the class described, a frame having means for attaching the same to a support, a pair of end brackets pivoted to the frame and suspended therefrom for lateral upwardly swinging movement in a vertical plane, a bar pivoted to the end bracket for endwise and upwardly swinging movement therewith, said bar having means for attaching a clothesline thereto, and a latch on the hanger yieldingly held in an operative position for holding the end brackets and the bar in their raised position, said latch having a cam member in the path of movement of one of the end brackets when the bar is swung upwardly, whereby the engagement of said end bracket with the cam-acting member will move the latch into an inoperative position and hold the same until the bar has passed the same.

25 12. In a hanger of the class described, a frame having means for attaching the same to a support, a bar having means for attaching a clothes-line thereto, a pair of pivoted links suspending the bar from the frame for endwise and upwardly swinging movement in a vertical plane, a latch pivoted to the frame and held by the force of gravity in an operative position for holding the bar in a raised position, and a cam on the latch normally in the path of movement of one of the links during its endwise and upwardly swinging movement, whereby the cam will be engaged by the respective link and moved thereby together with the latch into inoperative positions to permit said link to pass the cam and the latch.
